UNITED STATES PATENT OFFICE.

ARTHUR BOECKER, OF BARMEN-RITTERSHAUSEN, GERMANY.

ENVELOP AND THE LIKE FOR EXPLOSIVES.

1,096,014.

Specification of Letters Patent. Patented May 12, 1914.

Application filed November 6, 1913. Serial No. 799,497.

To all whom it may concern:

Be it known that I, ARTHUR BOECKER, manufacturer, subject of the German Emperor, residing at Barmen-Rittershausen, 5 Rhenish Prussia, Germany, have invented certain new and useful Improvements in Envelops and the like for Explosives, of which the following is a specification.

Before being filled into or inserted into shells, the explosive materials are furnished with an envelop of hard cardboard, which forms on the one hand a padding or cushion between metal and explosive, and on the other hand is intended to prevent chemical 10 reaction, such as would take place *e. g.* between picric acid and iron. In order that these envelops may be made to offer the requisite resistance for their purpose, they must have a rather large thickness of wall, where- 15 by of course the useful space in the envelops becomes limited in extent and the action of the shell is correspondingly weakened. The present invention obviates this defect by providing an envelop which instead of con- 20 sisting of the hitherto usual thick cardboard, consists of a thin textile material *e. g.* of muslin, linen or the like which is stiffened by means of paper-pulp, dextrin, lac, gypsum or other suitable material. The wall of the 25 envelop may be formed either of one or of several layers of the material chosen and by the application of pressure or the like be given the desired form, which in virtue of its stiffness, the wall retains. As material 30 for the envelop the so-called muslin paper (*nesselpapier*) may be advantageously em- 35 ployed.

The advantages of this new envelop of woven material consist firstly, in the envelop 40 being able to be made extremely thin but nevertheless having a high degree of strength and rigidity, whereby there is no danger of that which can easily occur with thin cardboard, *viz.*, unintentional tearing 45 or breakage of the walls; and secondly, in the useful space within the envelop being materially increased. Whereas in the larger cardboard envelops or boxes the walls must be 2-3 mm. in thickness, in the new box a 50 thickness of 0.4-0.5 mm. will suffice. This means that in boxes of *e. g.*, 200-500 mm. diam. and 700-1500 mm. length, such as are largely supplied for naval purposes, there is

an important increase in the explosive material obtained.

55

When the explosive is poured into the new envelop, the latter is laid in the pouring mold and, owing to the flexibility of the prepared textile material, exactly fits the wall of the mold. This is not the case with the 60 hard cardboard boxes hitherto used.

When the envelop is to be employed for solid explosive bodies, it is filled in the same manner as the cardboard boxes, *i. e.*, the envelop is drawn over the explosive and then 65 closed by means of a lid or cover. The envelop may, however, have a vertical subdivision and be provided with a narrow adhesive, joint or seam. There are half-rings 70 or disks of cardboard arranged above and below which correspond and fit against one another when the halves of the vertically divided casing are applied to the sides of the explosive and stuck together along the joints. The half rings or disks above and 75 below may be then connected by means of whole rings or disks which are stuck on. In the case of cardboard boxes the thick walls prevent this. Preparation with oil and so forth such as is customary in the case of 80 cardboard boxes can likewise be carried out, in each case to suit the material chosen.

One example of a two-part envelop in accordance with the present invention is shown in the accompanying drawing, wherein— 85

Figure 1 is a vertical section of the envelop, and Fig. 2 a plan.

Here *a*, *a* are the two semi-conoidal halves of the envelop-wall, which consist of impregnated textile material, and are given 90 their desired form by the application of pressure. Adhesively attached to them above and below are circular end pieces *b* and *c* similarly constituting the base piece and tip piece of the envelop respectively. 95

Having now particularly described and ascertained the nature of my said invention and in what manner the same is to be performed, I declare that what I claim is:

1. An envelop for explosives consisting of 100 a conoidal body adapted to fit the interior of a conical shell and two flat end pieces, the body being composed of light flexible material saturated with stiffening material, the same being in separable sections normally 105 adhering together in use.

2. A conoidal envelop for explosives for shells consisting of two longitudinal semi-conoidal sections of light flexible material saturated with stiffening material and two 5 correspondingly divided circular pieces constituting the end-piece and tip-piece of the envelop respectively.

In testimony whereof, I have signed my name to this specification in the presence of two subscribing witnesses.

ARTHUR BOECKER. [L. S.]
